[57] ABSTRACT

A single electrical circuit is capable of alternatively calculating an output voltage V_o according to the general formula,

$V_o = V_A (V_C/V_B)^n$ or $V_o = K \ln (V_C/V_B)^T$
 where V_A , V_B and V_C are circuit input voltages and n , K , and T , are determinable values of the circuit. A first relaxation oscillator may be selectively coupled to a second relaxation oscillator or to a chargeable capacitor supplied with constant current. The value of V_o is repeatedly adjusted as a function of decaying response time. V_o is computed when two response times are driven into equality.

MULTI-MODE COMPUTING CIRCUIT

BACKGROUND OF THE INVENTION

1. Field of the Invention

The present invention relates to an electrical circuit capable of calculating an output voltage V_o as a function of variable input voltages, V_A , V_B , and V_C , according to the general formulae,

$$V_o = V_A (V_C/V_B)^n \text{ or } V_o = K \ln (V_C/V_B)^T_1$$

where $\ln$ represents a natural logarithm and n , K , and T_1 are determinable constants of the circuit.

2. Description of the Prior Art

A digital computer is capable of calculating a plurality of mathematical modes, such as division, multiplication, and the like, only if programmed to perform the desired function. However, many of such digital computers involve complicated and expensive structure, rendering their use impractical for many potential users. Beyond the cost of the physical structure, the degree of technical sophistication needed to program and operate such computers further adds to their total cost.

A non-electrical system may often be reproduced in its electrical equivalency by an analog computer. While many mechanical elements have simple and inexpensive electrical analogs, still others require costly electrical hardware. Additionally, the assembly and operation of the analogous electrical circuit requires the exercise of a high degree of technical skill.

Still other computers are hybrid combinations of digital and analog logic. While unique capabilities may often be obtained with such systems, the inherent high costs of structure, programming, and operation are still present.

SUMMARY OF THE INVENTION

A single multi-mode computing circuit is capable of calculating an output voltage V_o as a function of variable input voltages V_A , V_B and V_C , according to the general formulae,

$$V_o = V_A (V_C/V_B)^n \text{ or } V_o = K \ln (V_C/V_B)^T_1,$$

where V_C is greater than V_B and n , K , and T_1 are determinable constants of the circuit.

The circuit has energizing means for simultaneously charging a first relaxation oscillator with V_C and a second relaxation oscillator with V_o for a determinable finite time period. After the time period expires, the oscillators are simultaneously permitted to decay. The voltages and response times required for V_C to fall to V_B and for V_o to fall to V_A are sensed and compared in first and second comparator means, respectively. Correction means are provided to adjust the value of V_o for urging the difference in the response times to decrease. Sequencing means are operated by the comparator means for causing V_o to be successively recalculated. When the response times are equal, the circuit calculates $V_o = V_A (V_C/V_B)^n$. Alternatively, an element of the second relaxation oscillator may be replaced; and a capacitor may be supplied with constant circuit, selectively dischargeable to ground. While the first relaxation oscillator decays, the capacitor is permitted to charge. The correction means adjusts and calculates V_o . The sequencing means causes V_o to be recalculated, thereby to compute $V_o = K \ln (V_C/V_B)^T_1$ when the response times are equal.

The time required by the circuit to calculate V_o is adjustable regardless of the general formula selected.

One object of the present invention is to provide a single electrical circuit capable of calculating an output voltage V_o as a function of variable input voltages V_A , V_B , and V_C , according to the general formulae, $V_o = V_A (V_C/V_B)^n$ or $V_o = K \ln (V_C/V_B)^T_1$, where V_C is greater than V_B and n , K and T_1 are determinable constants of the circuit.

Another object is to provide a computing circuit which calculates an output voltage V_o by driving the response times of two decaying relaxation oscillators into phase and frequency equality.

Another object is to provide a computing circuit capable of providing a variable analog output signal as a function of variable analog input signals through the use of intermediate digital logic.

Another object is to provide a computing circuit capable of varying the time required to obtain a desired calculation.

Another object is to provide a computing circuit wherein the output or calculated signal is sampled and employed as a feedback signal.

Another object is to provide a computing circuit wherein the calculation of V_o is mathematically exact.

Still another object is to provide a relatively simple and inexpensive computing circuit.

These and other objects and advantages will become apparent from the foregoing and ongoing specification, the drawings, and the appended claims.

BRIEF DESCRIPTION OF THE DRAWINGS

FIG. 1 is a schematic representation of the circuit producing an output voltage V_o as a function of input voltages V_A , V_B , and V_C .

FIG. 2 is a schematic wiring diagram of the circuit depicted in FIG. 1 and capable of performing the functions,

$V_o = V_A (V_C/V_B)^n$ or $V_o = K \ln (V_C/V_B)^T_1$, where n , K and T_1 are determinable constants of the circuit.

FIG. 3 is a graphical illustration of the operation of the circuit in calculating $V_o = V_A (V_C/V_B)^n$, as the input voltages are varied.

FIG. 4 is a graphical illustration of the operation of the circuit in calculating $V_o = K \ln (V_C/V_B)^T_1$, as the input voltages are varied.

FIG. 5 is an elevational view of a cylindrical pipe discussed in the hypothetical practical illustration.

FIG. 6 is a schematic view depicting the manner in which three circuits and a differential amplifier may be combined to solve the complicated equation of the hypothetical practical illustration.

DESCRIPTION OF THE PREFERRED EMBODIMENTS

Referring to FIG. 1, the inventive multi-mode computing circuit is generally indicated at 10 and is shown receiving three variable input voltages, V_A , V_B , and V_C , on circuit input terminals 11, 12 and 13, respectively, and producing an output voltage V_o at circuit output terminal 15 as a function of the input voltages. If V_C is greater than V_B , the single circuit 10 is alternatively capable of producing V_o according to the following general equations:

$$(Eqn. 1) V_o = V_A (V_C/V_B)^n,$$

where n is a determinable constant or,

$$(Eqn. 2) V_o = K \ln (V_C/V_B)^T_1, \text{ where } K \text{ and } T_1 \text{ are determinable constants.}$$

As used herein, the term "mode" refers to a mathematical calculation or computation, such as multiplication; division; raising a number (or a ratio) to a power; extracting a root from a number (or a ratio); taking the natural logarithm of a number (or a ratio); or multiplying a natural logarithm by a constant to obtain, for example, a logarithm to a different base. Either of the alternative general formulae specified above are capable of performing more than one mode of operation.

In Equation 1: if $V_B = 1$ and $n = 1$, $V_o = V_A V_C$ (simple multiplication); if $V_A = 1$ and $n = 1$, $V_o = V_C / V_B$ (simple division); if $n = 1$, $V_o = V_A (V_C / V_B)$ (a multiplier times a ratio); if $V_A = 1$, $V_B = 1$, and $n = 3$, $V_o = V_C^3$ (cube); if $V_A = 1$, $V_B = 1$, and $n = 1/3$, $V_o = V_C^{1/3}$ (cube root); and so forth.

Similarly, in Equation 2: if V_B , K , and T_1 each equal 1, $V_o = \ln V_C$ (natural logarithm of a number); if $K =$ a constant, and V_B and $T_1 = 1$, $V_o = K \ln V_C$ (constant times a natural logarithm of a number); and so on. Thus, several modes of operation may be obtained regardless of the general equation selected.

THE CIRCUIT (FIG. 2)

A computing circuit capable of calculating V_o as a function of the variable input voltages according to the general formulae specified in Equations 1 and 2 is schematically illustrated in FIG. 2.

The three input terminals 11, 12 and 13 are shown receiving their respective voltages, V_A , V_B , and V_C . The output voltage V_o is available at output terminal 15. The circuit broadly includes two identical voltage comparators A_1 and A_2 , an AND gate, a monostable multivibrator, a voltage source V , a constant current source i_K , two RC relaxation oscillators, a buffer amplifier, and a capacitor C_1 , along with a plurality of electronic (ES) and manual (MS) switches and resistors (R).

The identical voltage comparators A_1 and A_2 have a high input impedance and receive their input voltages at terminals 2 and 3 to produce an output signal at terminal 6. If the voltage on terminal 3 is greater than at terminal 2, the comparator will produce a positive output signal at terminal 6; if the voltage at terminal 3 equals that at terminal 2, the comparator will produce a null or zero signal at terminal 6; if the voltage at terminal 3 is less than that at terminal 2, the comparator will produce a negative output signal.

The monostable multivibrator may be excited or triggered into its quasi-stable state to produce a positive pulse output for a finite period of time, t_d , after expiration of which it reverts to its stable state having a negative output. Preferably, the multivibrator has an adjustable quasi-stable state to permit t_d to be varied, thereby to alter the length of time of the triggered positive pulse. With the capability of adjusting the length of time t_d that the monostable multivibrator remains excited in its quasi-stable state, the time required for the circuit to calculate V_o may be varied. This feature is of tremendous significance. For example, if the circuit is merely to perform a mathematical calculation, t_d may be set to a very small value, thereby enabling the circuit to rapidly calculate the value of V_o . However, if the circuit is employed to monitor a chemical process or the like, t_d can be set to a large value to afford a "wait and see" capability of operation. In this latter application, t_d could be adjusted to equal or approach one of the process parameters.

In the well known manner, the AND gate will produce a positive output only if its input signals are both positive. If either or both of its input signals are negative, the AND gate will maintain a negative output.

The buffer amplifier has a high input impedance and a low output impedance and has a gain of approximately one, which need not be stable or linear.

Input voltage V_A is applied to the computing circuit at input terminal 11 and is directed to terminal 3 of comparator A_2 through manual switch MS_4 and conductor 20. Input voltage V_B is applied at input terminal 12 and is directed to terminal 3 of comparator A_1 through conductor 21. Input voltage V_C is applied at terminal 13 and is directed to terminal 2 of comparator A_1 through conductor 22, electronic switch ES_1 , and conductors 23, 24.

A first relaxation oscillator network is connected to terminal 2 of comparator A_1 between conductors 23 and 24 by a conductor 25.

20 The first relaxation oscillator has a variable resistor R_1 connected to conductor 25 by a conductor 26, and connected to ground wire 28 by conductor 29; and has a capacitor C_1 connected in parallel with R_1 by conductors 30, 31 connected to conductor 25 and to ground wire 28, respectively. The first relaxation oscillator means includes this first relaxation oscillator network.

The calculated voltage V_o is supplied to terminal 2 of comparator A_2 from the buffer amplifier through conductors 33, 34 and 35, electronic switch ES_2 , and conductors 36, 37 and 38.

30 The second relaxation oscillator network is connected to terminal 2 of comparator A_2 between conductors 37 and 38 by a conductor 39, manual switch MS_1 , and conductor 40. The second oscillator has a resistor R_2 connected to conductor 40 by conductors 41 and 42 and manual switch MS_3 , and connected to ground wire 43; and has capacitor means such as a capacitor C_2 connected in parallel with R_2 by a conductor 44 connected to conductor 40 and by conductor 45 connected to ground wire 43. The second relaxation oscillator means includes this second relaxation oscillator network.

40 Manual switch MS_1 may be moved to its phantom position to disconnect the second relaxation oscillator network from terminal 2 of comparator A_2 and to connect conductor 40 to a constant circuit source i_K .

Manual switch MS_2 may be selectively closed to provide a shunt around electronic switch ES_2 and is connected by conductor 46 between conductors 36 and 37, and by conductor 48 between conductors 35 and 34.

50 Manual switch MS_3 may be moved to its phantom position to disconnect R_2 from conductor 42 and to connect a branch in parallel with C_2 including conductor 49, electronic switch ES_3 , and conductor 50 connected to ground wire 43.

55 Manual switch MS_4 may be moved to its phantom position to disconnect input voltage V_A and to connect conductor 20 to conductor 41 through an intermediate conductor 51.

The output signal produced at terminal 6 of comparator A_1 is received as a first input signal to the AND gate through conductor 52. Similarly, the output signal produced at terminal 6 of comparator A_2 is received as a second input signal to the AND gate through conductor 53. If the signals in conductors 52 and 53 are both positive, the AND gate will trigger the monostable mul-

tivibrator into its quasi-stable state through conductor 54. When so excited, the multivibrator produces a positive pulse output for a predetermined period of time, t_d , which is employed to close ES₁, ES₂, and ES₃ for a corresponding period of time, as shown schematically by dashed lines 55, 56, 58, 59 and 60. The sequencing means includes the AND gate.

A voltage source V is grounded through a series circuit including conductor 61, electronic switch ES₄, resistors R₄ and R₃, electronic switch ES₅, and ground wire 62. Electronic switches ES₄ and ES₅ are operated by the comparator output signals in conductors 53 and 52, respectively, as shown schematically by dashed lines 63 and 64. Therefore, ES₅ will close when the output signal of comparator A₁ is positive, and open when it is negative. Similarly, ES₄ will close when the output signal of comparator A₂ is positive, and open when it is negative. The correction means thus comprises a voltage supply circuit including voltage source V, ES₄, and resistor R₄; and a voltage drain circuit including R₃, ES₅ and ground wire 62.

A capacitor C_s is grounded by ground wire 65 and is connected between resistors R₃ and R₄ by series conductors 66 and 68. Conductor 32 is shown connected between conductors 66 and 68.

The energizing means includes the monostable multivibrator and electronic switches ES₁, ES₂ and ES₃. The first electronic switch means comprises ES₁; and second electronic switch means comprises ES₂; and the third electronic switch means includes ES₃.

The first and second comparator means includes comparators A₁ and A₂, respectively.

As used herein, the term "relaxation oscillator means" broadly includes other known and functionally equivalent RC and RL circuits wherein a voltage may be permitted to decay to a lower value in a reproducible manner.

Derivation of $V_0 = V_A (V_C/V_B)^n$

With the four manual switches MS₁, MS₂, MS₃ and MS₄ moved to the positions indicated by the solid lines in FIG. 2, the circuit is prepared to calculate $V_0 = V_A (V_C/V_B)^n$.

The three input voltages, V_A , V_B and V_C , are each applied to their respective input terminals, 11, 12 and 13. V_C is either selected or scaled to a greater value than V_B . Similarly, the internal voltage source V is provided at a greater value than V_0 .

Assume that initially the circuit is arranged such that all electronic switches are open and the several capacitors are discharging to low values. V_B and V_A will be applied to terminals 3 of comparators A₁ and A₂, respectively. Since ES₁ is open, V_C will not be applied to terminal 2 of comparator A₁. Since ES₂ is open, V_0 will not be applied to terminal 2 of comparator A₂. Therefore, the voltage at terminals 3 will be greater than that at terminals 2 of both comparators A₁ and A₂.

At this instant, the output signals of both comparators will simultaneously be positive. ES₄ and ES₅ will be closed, grounding voltage source V through series resistors R₃ and R₄ and charging capacitor C_s to some value. Receiving two positive input signals, the AND gate triggers the monostable multivibrator into its quasi-stable state to close ES₁ and ES₂ and to apply V_C and V_0 to comparators A₁ and A₂, respectively. Since V_C is greater than V_B , the output of comparator A₁ will

flip from positive to negative, opening ES₅, and adjusting the value of V_0 .

If V_0 is greater than V_A , the output signal of comparator A₂ will simultaneously flip from positive to negative, opening ES₄. When ES₄ and ES₅ are both open, the voltage across capacitor C_s is fixed. Accordingly, the value of V_0 will be fixed.

ES₁ and ES₂ are closed when the multivibrator is triggered into its quasi-stable state. During this time t_d , capacitor C₁ is charged to V_C and capacitor C₂ is charged to V_0 .

After time period t_d expires, the multivibrator reverts to its stable state, opening ES₁, ES₂, and ES₃. Both capacitors of the relaxation oscillator networks begin to decay which is sensed at terminals 2 of the respective comparators. During such decay, the current in the first oscillator is given by the formula, $i_1 = i_0 e^{-t/R_1 C_1}$. Initially, $i_0 = V_C/R_1$. Substituting, $i_1 (V_C/R_1) e^{-t/R_1 C_1}$. When the first relaxation oscillator decays to the flip voltage V_B , the current will be $i_{at \text{ flip}} = V_B/R_1$. Substituting for i_1 and solving for Δt_1 , the time required for this decay:

$$V_B/R_1 = (V_C/R_1) e^{-\Delta t_1/R_1 C_1}$$

$$V_B/V_C = e^{-\Delta t_1/R_1 C_1}$$

$$V_C/V_B = e^{+\Delta t_1/R_1 C_1}$$

$$\Delta t_1 = \ln(V_C/V_B) R_1 C_1$$

where Δt_1 = response time of first relaxation oscillator to decay from V_C to V_B .

Similarly, the decaying current in the second oscillator is given by the formula:

$$i_2 = i_0 e^{-t/R_2 C_2}$$

When ES₂ opens,

$$i_0 = V_0/R_2$$

or,

$$i_2 = (V_0/R_2) e^{-t/R_2 C_2}$$

After the second oscillator decays from V_0 to V_A , the flip voltage,

$$i_{2 \text{ at flip}} = V_A/R_2$$

Substituting and solving for Δt_2 :

$$V_A/R_2 = (V_0/R_2) e^{-\Delta t_2/R_2 C_2}$$

$$V_A/V_0 = e^{-\Delta t_2/R_2 C_2}$$

$$V_0/V_A = e^{+\Delta t_2/R_2 C_2}$$

$$\Delta t_2 = \ln(V_0/V_A) R_2 C_2$$

where t_2 = response time for second oscillator to decay from V_0 to V_A .

If Δt_1 is less than Δt_2 , ES₅ will close before ES₄, draining C_s and decreasing V_0 until $V_0 = V_A$. Conversely, if the second oscillator decays to flip A₂ before the first oscillator decays to flip A₁, Δt_2 will be less than Δt_1 , closing ES₄ before ES₅ to charge C_s and to increase V_0 . Thus, the value of V_0 is adjusted and caused to be readjusted on every sequence to urge the response times to equal each other.

Finally, when the response times are equal such that

$$\Delta t_1 = \Delta t_2$$

$$\ln(V_C/V_B) R_1 C_1 = \ln(V_0/V_A) R_2 C_2$$

or,

$$V_0 = V_A (V_C/V_B) R_1 C_1 / R_2 C_2$$

60 If $n = R_1 C_1 / R_2 C_2$, the following derivation obtains:

$$V_0 = V_A (V_C/V_B)^n$$

where n may be selectively varied by adjusting variable resistor R₁.

Derivation of $V_0 = K \ln(V_C/V_B) T_1$

With manual switches MS₁, MS₂, MS₃, and MS₄ moved to the positions indicated by the phantom lines of FIG. 2, the circuit is prepared to calculate $V_0 = K \ln$

$(V_C/V_B)^T_1$ where K and T_1 are determinable constants of the circuit. When so moved to their phantom positions, MS_1 connects C_2 to a constant current source i_K , MS_2 provides a shunt around ES_2 , MS_3 disconnects V_A and connects C_2 to terminal 3 of comparator A_2 .

In this configuration, the constant current source i_K is continuously applied to capacitor C_2 . When ES_3 closes, the current source is grounded and C_2 is permitted to discharge.

With the monostable multivibrator in its stable state, ES_1 and ES_3 are open. Voltage V_B is applied to terminal 3 of comparator A_2 , generating a positive A_2 comparator output signal to the AND gate and closing ES_5 . Since ES_4 is open, the current source begins to charge C_2 which is also sensed on terminal 3 of comparator A_2 . Capacitor C_2 charges according to the formula,

$$E_{C_2} = \frac{1}{C_2} \int_{t_0}^{t_2} i_K dt$$

Since, $i = i_K$, a constant,

$$E_{C_2} = \frac{i_K}{C_2} \int_{t_0}^{t_2} dt = \frac{i_K}{C_2} (t_2 - t_0) = \frac{i_K}{C_2} (\Delta t)$$

In some time interval Δt_2 , capacitor C_2 will have charged with a voltage E_{C_2} equal to V_0 . Substituting and solving for t_2 :

$$E_{C_2} = V_0 = i_K/C_2 (\Delta t_2)$$

$$\Delta t_2 = V_0 C_2 / i_K$$

Again V_0 is adjusted and readjusted such that the response time of the capacitor to the value of V_0 is urged to equal the response time of the first relaxation oscillator during decay. Finally, the response times will be urged into equality, or,

$$\Delta t_1 = \Delta t_2$$

$$\Delta t_1 = \ln (V_C/V_B) R_1 C_1$$

$$\Delta t_2 = V_0 C_2 / i_K$$

Substituting and solving for V_0 ,

$$\ln (V_C/V_B) R_1 C_1 = V_0 C_2 / i_K$$

$$V_0 = i_K/C_2 \ln (V_C/V_B) R_1 C_1$$

or,

$$V_0 = K \ln (V_C/V_B) T_1$$

where $T_1 = R_1 C_1$ and $K = i_K/C_2$, all determinable constants of the circuit.

When performing this function, the relaxation oscillator means includes first relaxation oscillator.

Operation of $V_0 = V_A (V_C/V_B)^n$ Function (FIG. 3)

FIG. 3 graphically represents the operation of the circuit in computing the function, $V_0 = V_A (V_C/V_B)^n$. The numbered pulses of the monostable multivibrator are vertically aligned with the corresponding peak voltages in C_1 above and C_2 below, respectively.

At the first and second mono pulses, the circuit is depicted calculating $V_0 = 4$ when $V_A = 2$, $V_B = 1$, and $V_C = 2$. The response times Δt_1 and Δt_2 are shown to be equal, indicating that $V_0 = 4$ is the desired calculation.

Voltage V_A is then increased from 2.0 to 2.5 in the interval between pulse 2 and the completion of pulse 3. Capacitor C_1 is again charged with V_C and is permitted to decay to V_B . Since $V_0 = 4$ is still greater than the increased value of V_A , capacitor C_2 is again charged with $V_0 = 4$, but decays to the lesser value, $V_A = 2.5$, faster than V_C decays to V_B . In this situation, Δt_2 is less than Δt_1 . Hence, ES_4 closes before ES_5 , increasing V_0 to some higher adjusted value, as illustrated at sequential

pulse 4. Voltage V_C still decays to voltage V_B in the same time, Δt_1 . However, adjusted voltage V_0 now decays from a higher value, tending to increase Δt_2 . The response between pulses 4 and 5 illustrates V_0 at some intermediately adjusted value. Upon decay, Δt_2 is still less than Δt_1 , again causing V_0 to increase. Sequential pulse 5 represents a readjusted value of V_0 . When V_0 has performed the desired calculation, Δt_1 will equal Δt_2 , as shown in the intervals between pulses 5 and 6 and pulses 7 and 8.

If V_C is decreased from 2.0 to 1.5 between pulses 7 and 8, capacitors C_1 will charge to the now lowered value of $V_C = 1.5$. The change in V_C is not immediately known to V_0 , which again charges to $V_0 = 5$. After t_d expires, V_C will decay to V_B before V_0 will decay to V_A or, Δt_1 is less than Δt_2 . ES_5 will open before ES_4 to adjust V_0 to some decreased value, represented at pulse 9. Voltage V_0 will be sequentially readjusted until Δt_1 equals Δt_2 , as represented by the equal response times between pulses 10 and 11. When Δt_1 equals Δt_2 , V_0 equals 3.75, the desired computation.

Now if V_B is decreased from 1.0 to 0.75 between pulses 11 and 12, capacitor C_1 will take longer to decay to the decreased value of V_B than capacitor C_2 will take to decay from the previous V_0 to V_A or, Δt_1 will be greater than Δt_2 . Hence, ES_4 will close before ES_5 , causing V_0 to increase as shown at pulse 13. Again V_0 is sequentially readjusted to urge Δt_2 to equal Δt_1 , which situation is illustrated between pulses 14 and 15, and pulses 15 and 16.

Voltages V_C and V_B are shown increased to 2.0 and 1.0, respectively, between pulses 16 and 17. At pulse 17, C_1 will charge to the higher value of V_C and take longer to decay to the lower value of V_B , as shown between pulses 17 and 18. If V_A is decreased to 2 between pulses 17 and 18, V_0 will also take longer to decay. Electronic switch ES_4 will open first, increasing V_0 at pulse 18. Finally, Δt_1 will equal Δt_2 and the desired computation will have been performed, as in pulses 19 and 20, and pulses 21 and 22.

By varying adjustable resistor R_1 , the exponent n can be varied according to the formula, $n = R_1 C_1 / R_2 C_2$. In the response graphically depicted in the rightward portion of FIG. 3, R_1 has been adjusted such that $n = 2$ to perform a squaring function. The response times are initially shown to be equal between pulses 28 and 29 and pulses 29 and 30 so that $V_0 = 2.25$ when $V_A = 1$, $V_B = 1$, and $V_C = 1.5$. If V_C is increased to 2.0 between pulses 30 and 31, V_0 will charge to this higher value at pulse 31. When ES_1 and ES_2 are open, the response time of the first oscillator to decay from V_C to V_B will take longer than the corresponding decay of the second oscillator from the previous V_0 to V_A . Hence, Δt_1 will be greater than Δt_2 , causing ES_4 to open first and adjust the value of V_0 , as represented in sequential pulse 32. The adjustment of V_0 continues until Δt_1 equals Δt_2 , indicating performance of the desired computation, as indicated at pulses 33, 34 and 35.

Operation of $V_0 = K \ln (V_C/V_B) T_1$ Function (FIG. 4)

FIG. 4 graphically represents the operation of the circuit in computing $V_0 = K \ln (V_C/V_B) T_1$. If initially, $V_B = 4$, $V_C = 8$, $K = 1$, and $T_1 = 1$, the circuit is initially shown as calculating $V_0 = \ln (2)$ at pulses 1, 2 and 3.

When the monostable multivibrator closes ES_1 and ES_3 for time t_d , C_1 is charged with V_C and C_2 is permitted to discharge through conductors 44, 41, 42, 49, 50 and 43. Hence, when C_1 is permitted to charge, C_2 is permitted to discharge. After t_d expires, ES_1 and ES_3

open, permitting capacitor C_1 to decay and permitting capacitor C_2 to be charged with i_K . Hence, C_1 is decaying when C_2 is charging.

If V_B is decreased to 1.0 between pulse 4 and pulse 5, C_1 will take longer to decay to the lowered value of V_B . If capacitor C_2 charges to the value of V_0 first, Δt_2 will be less than Δt_1 , causing ES_4 to close first, increasing V_0 . Again the system urges Δt_1 to equal Δt_2 as shown between pulses 6 and 7 and pulses 7 and 8. Thus, if $V_C = 8$ decays to $V_B = 1$ in Δt_1 , C_2 will charge to a higher value of $V_0 = 1n$ (8) in the same time, indicating performance of the desired computation.

If V_C is increased to 15 between pulses 7 and 8, C_1 will be charged with V_C during pulse 8. Hence, Δt_1 will be longer for capacitor C_1 to decay from 15 to 1; C_2 will cause ES_4 to close first, increasing V_0 . At $\Delta t_1 = \Delta t_2$, $V_0 = 1n$ (15) will be calculated.

If V_B is increased to 5 between pulses 10 and 11, the response time of C_1 in decay will be shortened, opening ES_5 before ES_4 , to decrease V_0 . As Δt_2 is shortened, capacitor C_2 charges to a lower value, finally when $\Delta t_1 = \Delta t_2$, $V_0 = 1n$ (5) is calculated.

PRACTICAL ILLUSTRATION

For purposes of illustrating the utility of further combinations of the inventive circuit, assume that it is desired to calculate the heat conducted through some or all of the pipes in an oil refinery.

Referring to FIG. 5, a long hollow pipe 80 is depicted as having an inner radius r_i and an outer radius r_o . Assume that a fluid heats the inner surface to T_i while the outer surface is at temperature T_o . The rate of heat conduction, q_K is given by the general formula,

$$q_K = 2\pi K L (T_i - T_o) / \ln (r_o / r_i)$$

where

2π = a constant

K = coefficient of thermal conductivity

L = length

T_i = temperature inside pipe

T_o = temperature outside pipe

r_o = outer radius

r_i = inner radius

Three circuits and a differential amplifier may be uniquely combined to calculate q_K as a function of multiple variables, as best shown in FIG. 6.

In FIG. 6, circuit No. 1 is prepared to calculate $V_0 = V_A (V_C / V_B)^{n=1}$. The input voltages are selected such that $V_A = K$, a variable; $V_B = 1/2\pi$, a constant; and $V_C = L$, a variable. Substituting the input voltages into the general equation produces an output voltage $V_{01} = 2\pi K L$.

Circuit No. 2 is prepared to calculate $V_{02} = (i_K / C_2) 1n (V_C / V_B) T_1$, where $T_1 = 1$, and $i_K / C_2 = K = 1$. Input voltages V_B and V_C are selected to represent the radii, r_i and r_o , respectively. Substituting the input voltages of V_B and V_C into the general equation produces an output signal $V_{02} = 1n (r_o / r_i)$.

A differential amplifier receives the voltages analog of two temperatures, T_i and T_o , produces an output signal equal to their difference, $(T_i - T_o)$.

Circuit No. 3 is prepared to calculate $V_0 = V_A (V_C / V_B)^{n=1}$ with $n=1$. The output voltage V_{01} of the circuit No. 1 is received as input voltage V_{A3} to circuit No. 3; the output voltage V_{02} of circuit No. 2 is received as input voltage V_{B3} ; and the output voltage of the differential amplifier, $(T_i - T_o)$, is received as input voltage V_{C3} . Sub-

stituting these input voltages into circuit No. 3 produces an output signal, $V_{03} = 2\pi K L (T_i - T_o) / [1n (r_o / r_i)]$, the desired computation. Thereafter, any of the variables K , L , T_i , T_o , r_i , and r_o may be varied.

The foregoing practical illustration is intended merely to demonstrate that two or more of the unique circuits herein disclosed may be combined to perform a more complicated computation. The practical illustration further demonstrates that the inventive circuit may be combined with a differential amplifier, as needed. Should an equation involve addition, a summing amplifier could be used.

The various electrical and electronic components discussed hereinabove are well known to the skilled in the art and therefore require no more specific description.

What is claimed is:

1. A multi-mode computing circuit capable of calculating an output voltage V_0 as a function of three variable input voltages, V_A , V_B , and V_C , according to the general formula, $V_0 = V_A (V_C / V_B)^n$, where V_C is greater than V_B and n is a determinable value of the circuit, comprising:

25 first and second relaxation oscillator means; energizing means for simultaneously charging said first oscillator means with V_C and said second oscillator means with V_B for a finite time period and for permitting decay of both of said oscillator means after said time period expires;

30 first comparator means for comparing the voltage in said first oscillator means with V_B and for sensing the response time of said first oscillator means during decay;

35 second comparator means for comparing the voltage in said second oscillator means with V_A and for sensing the response time of said second oscillator means during decay;

40 correction means controlled by the voltages compared at said first and second comparator means for adjusting the value of V_0 and for urging the difference of said response times to decrease; and sequencing means operated by said first and second comparator means for successively activating said energizing means after V_0 has been adjusted to cause V_0 to be readjusted and to calculate $V_0 = V_A (V_C / V_B)^n$ when said response times are equal.

2. The circuit of claim 1 wherein said energizing means permits simultaneous decay of both of said oscillator means.

3. The circuit of claim 1 wherein said energizing means is adjustable to permit said finite time period to be varied.

4. The circuit of claim 2 wherein said first oscillator means includes a RC circuit having a resistor R_1 arranged in parallel with a capacitor C_1 .

5. The circuit of claim 4 wherein said second oscillator means is a RC circuit having a resistor R_2 arranged in parallel with a capacitor C_2 .

6. The circuit of claim 5 wherein $n = R_1 C_1 / R_2 C_2$.

7. The circuit of claim 6 wherein R_1 is an adjustable resistor for permitting n to be varied.

8. The circuit of claim 1 wherein said first comparator means is a voltage comparator capable of generating a positive output signal when the voltage in said first oscillator means is greater than V_B , a negative signal when such voltage is less than V_B , and a null signal when such voltage is equal to V_B .

9. The circuit of claim 1 wherein said second oscillator means is a voltage comparator capable of generating a positive output signal when the voltage in said second oscillator means is greater than V_A , a negative signal when such voltage is less than V_A , and a null signal when such voltage is equal to V_A .

10. The circuit of claim 3 wherein said energizing means includes first electronic switch means between V_C and said first oscillator means, second electronic switch means between V_o and said second oscillator means, and a monostable multivibrator operatively associated with said first and second electronic switch means to close said switch means when said multivibrator is excited into its quasi-stable state and to open said switches when said multivibrator reverts to its stable state.

11. The circuit of claim 10 wherein said monostable multivibrator is adjustable to vary said finite time period.

12. The circuit of claim 1 wherein said sequencing means includes an AND gate.

13. The circuit of claim 1 wherein said correction means includes a voltage supply circuit operated by said second comparator means to increase V_o when said response time of said second oscillator means is less than said response time of said first oscillator means.

14. The circuit of claim 13 wherein said correction means further includes a voltage drain circuit operated by said first comparator means to decrease V_o when said response time of said first oscillator means is less than said response time of said second oscillator means.

15. The circuit of claim 14 wherein said correction means further includes capacitor arranged in parallel with said voltage drain circuit.

16. The circuit of claim 15 further comprising a buffer amplifier between said correction means and said second comparator means.

17. A multi-mode computing circuit capable of calculating an output voltage V_o as a function of two variable input voltages, V_B and V_C , according to the general formula, $V_o = K \ln (V_C/V_B)^T_1$, where V_C is greater than V_B and where C and T_1 are determinable values of the circuit comprising:

relaxation oscillator means;
a source of constant current;
capacitor means supplied with said constant current; energizing means for simultaneously charging said oscillator means with V_C and for draining said capacitor means for a finite time period and for permitting said oscillator means to decay and said capacitor means to charge after said time period expires;

first comparator means for comparing the voltage in said oscillator means with V_B and for sensing the response time of said oscillator means during decay;

second comparator means for comparing the voltage in said capacitor means with V_o and for sensing the response time of such capacitor means during charging;

correction means controlled by the relative voltages compared at said first and second comparator means to adjust V_o for urging the difference between said oscillator response time and said charg-

ing capacitor means response time to decrease; and sequencing means for successively activating said energizing means after V_o has been adjusted to cause V_o to be readjusted and to calculate $V_o = K \ln (V_C/V_B)^T_1$ when said response times are equal.

18. The circuit of claim 17 wherein said energizing means simultaneously permits said capacitor means to charge and said oscillator means begins to decay.

19. The circuit of claim 18 wherein said oscillator means includes an RC circuit having a resistor R_1 arranged in parallel with a capacitor C_1 .

20. The circuit of claim 19 wherein $T_1 = R_1 C_1$.

21. The circuit of claim 20 wherein R_1 is an adjustable resistor for permitting T_1 to be varied.

22. The circuit of claim 17 wherein said energizing means is adjustable to permit said finite time period to be varied.

23. The circuit of claim 22 wherein said first comparator means is a voltage comparator capable of generating a positive output signal when the voltage in said oscillator means is greater than V_B , a negative signal when such voltage is less than V_B , and a null signal when such voltage is equal to V_B .

24. The circuit of claim 18 wherein said second comparator means is a voltage comparator capable of generating a positive output signal when the voltage in said capacitor means is greater than V_o , a negative signal when such voltage is less than V_o , and a null signal when such voltage is equal to V_o .

25. The circuit of claim 22 wherein said energizing means includes first electronic switch means between V_C and said oscillator means, third electronic switch means arranged in parallel with said capacitor means, and a monostable multivibrator operatively associated with said first and third electronic switch means to close said switch means when said multivibrator is excited into its quasi-stable state and to open said switch means when said multivibrator reverts to its stable state.

26. The circuit of claim 25 wherein said monostable multivibrator is adjustable to vary said finite time period.

27. The circuit of claim 18 wherein said sequencing means includes an AND gate.

28. The circuit of claim 18 wherein said correction means includes a voltage supply circuit operated by said second comparator means to increase V_o when said response time of said capacitor means during charging is less than said response time of said oscillator means during decay.

29. The circuit of claim 28 wherein said correction means further includes a voltage drain circuit operated by said first comparator means to decrease V_o when said response time of said oscillator means during decay is less than said response time of said capacitor means during charging.

30. The circuit of claim 29 wherein said correction means further includes a capacitor arranged in parallel with said voltage drain circuit.

31. The circuit of claim 30 further comprising a buffer amplifier between said correction means and said second comparator means.

32. The circuit of claim 17 wherein said capacitor means is a capacitor.

UNITED STATES PATENT OFFICE
CERTIFICATE OF CORRECTIONPatent No. 3,784,803 Dated January 8, 1974Inventor(s) Thomas A. Brendle

It is certified that error appears in the above-identified patent and that said Letters Patent are hereby corrected as shown below:

Title page: the identified Attorney should be --Sommer & Weber--;
ABSTRACT, line 4: the second equation should be -- $V_0 = K \ln(V_C/V_B)$ T_1 --;
Col. 1, line 41: "energizing" should be --energizing--;
Col. 2, line 36: the first equation should be -- $V_0 = V_A (V_C/V_B)^n$ --;
Col. 6, line 18: after "Substituting," the equation should be
-- $i = (V_C/R_1) e^{-t/R_1 C_1}$ --;
Col. 7, line 22: "t₂" should be -- Δt_2 --;
Col. 8, line 12: "cápacitors" should be --capacitor--;
Col. 9, line 21: "value, finally" should be -- value. Finally--;
, line 47: "V₀" should be -- V_{0_1} --;
Col. 10, line 2: the equation should be
-- $V_{0_3} = 2 \pi K L (T_i - T_o) / [\ln(r_i/r_o)]$ --;
, line 14: "the" should be --those--;
Claim 15, line 2: "includes capacitor" should be --includes a capacitor--;
Claim 17, line 5: "C" should be --K--;
Claim 18, line 3: "begins" should be deleted.

Signed and sealed this 23rd day of April 1974.
